UNITED STATES PATENT OFFICE

164,547

MAGAZINE RACK

Wilfred C. Becker, Allen Park, Mich., assignor to
Built-Rite Manufacturers, Detroit, Mich., a co-
partnership

Application June 26, 1951, Serial No. 15,667

Term of patent 14 years

(Cl. D33—2)

To all whom it may concern:

Be it known that I, Wilfred C. Becker, a citizen of the United States of America and resident of the city of Allen Park, county of Wayne, State of Michigan, have invented a new, original, and ornamental Design for Magazine Rack, of which the following is a specification, reference being had to the accompanying drawing, forming a part thereof, wherein:

Fig. 1 is a perspective view of a magazine rack embodying my new design;

Fig. 2 is a side elevational view of the magazine rack illustrated in Fig. 1; and

Fig. 3 is a front elevational view of the magazine rack illustrated in Fig. 1.

I claim:

The ornamental design for a magazine rack, as shown.

WILFRED C. BECKER.
